US00D887349S

(12) **United States Design Patent** (10) **Patent No.:** **US D887,349 S**
(45) **Date of Patent:** **** Jun. 16, 2020**

(54) **MODULAR SMARTPHONE INDUCTIVE CHARGING STATION**

(71) Applicant: **Scosche Industries, Inc.**, Oxnard, CA (US)

(72) Inventors: **Yasuhiro Yamamoto**, Thousand Oaks, CA (US); **Mark Larson**, Camarillo, CA (US); **Vince Alves**, Oxnard, CA (US)

(73) Assignee: **Scosche Industries, Inc.**, Oxnard, CA (US)

(**) Term: **15 Years**

(21) Appl. No.: **29/675,690**

(22) Filed: **Jan. 4, 2019**

CLAIM

The ornamental design for a modular smartphone inductive charging station, as shown and described.

DESCRIPTION

FIG. 1 is a front perspective view showing a modular smartphone inductive charging station of the present invention;

FIG. 2 is a top view thereof;

FIG. 3 is a front view thereof;

FIG. 4 is a rear view thereof;

FIG. 5 is a right side view thereof;

FIG. 6 is a left side view thereof; and,

FIG. 7 is bottom view thereof.

The broken lines in the figures depict environmental structure and portions of the modular smartphone inductive charging station that form no part of the claimed design.

1 Claim, 3 Drawing Sheets
